UNITED STATES PATENT OFFICE.

GEORGE THOMPSON, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed May 17, 1927. Serial No. 192,116.

This invention relates to telephone exchange systems and its object is to improve systems for the establishment and control of toll switching connections.

5 According to the invention, current for ringing the called subscriber's line is supplied from the final switch, but in case the called subscriber is recalled ringing current for this purpose is applied at a preceding group selector under control of the operator, the selection of the proper kind of current at the group selector for partly line calls being under control of the final switch and independent of the operator.

10 The invention is illustrated in a toll system employing automatic selective switches of the retractive control type the movement of which is controlled by a common register sender. The toll operator by means of a dialing cord circuit extends the toll connection to an automatic switch and records the called line designation on an idle register sender. The sender thereupon controls the switches to extend the connection to the called line.

15 Since the subscribers' lines seized by the final switch may include party lines, different kinds of ringing current must be supplied. The party lines are provided with a set of terminals per station and all lines requiring a given kind of ringing current are segregated to appear before the same group of final switches. These finals are arranged to apply ringing current in the proper manner for signaling the party line substations to which

20 they have access.

On the connection first being extended to a called party line the called substation is signaled by ringing current supplied from the final switch the same as for a local connection, but under control of the toll operator. In case the toll operator wishes to recall the called subscriber it is necessary that she be provided with means for causing the application of the proper kind of ringing current to the called line. It is also desirable that this be done without releasing and reestablishing the connection. Accordingly the present invention contemplates an arrangement in which the final switch, which identifies the kind of ringing current needed, causes a record to be set up in a preceding group selector in the series. This record in the group selector becomes effective under the control

of the toll operator when the recall is made to cause the application of ringing current from the group selector. In this manner the final switch is not disturbed in any way, it is not necessary to release and reestablish the connection and no special means is required for rendering the ringing current source at the final switch effective to rering the called subscriber.

55 The drawing, comprising four sheets to be arranged in consecutive order, discloses enough of a telephone system to enable an understanding of the invention.

Fig. 1 shows a toll operator's cord circuit and also illustrates a toll connection extended to her position.

60 Fig. 2 shows an incoming or first group selector to which toll connections are extended. It also illustrates diagrammatically a common register sender.

65 Fig. 3 shows a diagram of a second group selector.

70 Fig. 4 shows a final selector switch having access to called lines.

The toll operator's cord circuit 130 may be of any suitable design, the particular circuit shown being similar to that shown and described in detail in the patent to Stokely, No. 1,474,008, granted November 13, 1923 and in the application of Stokely, Serial No. 21,756, filed April 9, 1925 Patent No. 1,653,789, granted Dec. 27, 1927.

80 The selector switches shown in Figs. 2, 3 and 4 are of the power drive rotary type the construction of which is illustrated in the patent to McBerty, No. 1,097,868, granted May 26, 1914. The operation and control of 85 these switches are in general the same as disclosed in the patent to McBerty and Polinkowsky, No. 1,137,223, granted April 27, 1915.

90 A general outline having been given of the system the detailed operation will now be explained. For this purpose assume that the subscriber of line 100 wishes to extend a toll connection to a subscriber on the party line 427. The calling subscriber initiates the call in the usual manner which is answered by an operator at position 120. After the necessary record is made a connection is established in any suitable manner between the toll operator and the calling line 100. The completed connection between the toll operator and the calling line is made by the insertion of plug

102 of the cord circuit 130 into jack 101. The toll operator, after receiving the number of the called line, seizes the plug 103 and tests the jack 203 of the trunk leading to the incoming 5 switch shown in Fig. 2. If the trunk is idle she inserts the plug 103 in jack 203 completing a circuit as follows: from the grounded sleeve of the jack 203, sleeve of the plug 103, right winding of relay 107, windings of relays 106 and 105 to battery. The relay 105 operates but relay 106 being marginal does not attract its armature. The insertion of the 10 plug in the jack also completes a circuit for relay 200. This circuit may be followed from battery through the winding of the relay, lower left contact of sequence switch spring 201, upper left contact of said spring, over the ring of the trunk through the ring of jack 203 and plug 103, normal contact of 15 relay 109, normal contact or ringing key R' K', winding of coil 110, relay 108, normal contact of relay 106, winding of coil 110, upper normal contact of key R' K', front contact of relay 105, normal contact of relay 109, 20 thence over the tip of the connection through the left contacts of spring 202 to ground.

Relay 200 operates and closes a circuit as follows for driving the sequence switch out of position 1 and into position 3: ground 30 through the front contact of relay 200, right contact of spring 206, through the winding of the sequence switch magnet 205 to battery. When the sequence switch reaches position 2 1/4, a new circuit is closed for relay 206 traceable from battery through the winding of the relay, conductor 223, upper left contact of spring 207, back contact of test relay 208, upper right contact of spring 209 to ground.

In position 3 of sequence switch 205 the 40 sender selector switch, comprising the brushes shown at the bottom of Fig. 2, is operated to select an idle register sender 260. The brushes of the sender selector switch are driven by a power magnet 212 and the circuit for this magnet may be traced from battery through its winding, upper right and lower left contacts of spring 213 to ground at the front contact of relay 200. The test for an idle sender is made by the test relay 208. 45 The circuit for this purpose may be traced from ground through the lower right contact of spring 209, right high resistance winding of relay 208, lower right contact of spring 228 to the test brush 211. When an idle sender is reached, battery of the proper potential being connected to the test terminal in the switch, the relay 208 operates and at its back contact opens the circuit of relay 200 which releases and opens the circuit of the 50 power magnet 212 causing the sender selector to come to rest. The relay 200 in releasing closes a circuit from ground to its back contact, lower left contact of spring 206 to the sequence switch magnet 205, driving the sequence switch out of position 3 and into posi-

tion 4. In position 4 of the sequence switch a circuit is completed from one pole of battery through the usual impulse relay in the sender 260, thence over conductor 222, brush 220, upper contacts of spring 201, thence over the 70 ring side of the trunk to the jack and plug, normal contact of relay 109, thence as previously traced through the winding of relay 108 and returning over the tip of the connection through the lower contacts of 75 spring 202, brush 219, conductor 221 to the other pole of battery in the sender. This circuit conditions the sender for the receipt of impulses and also operates the relay 108 to cause the illumination of lamp 116. 80 The operator seeing the lamp lighted at this time throws the dialing key DK. This key completes a circuit from ground to its lower contact, winding and normal contact of relay 109, winding of relay 111 to battery. 85 Relay 111 operates but relay 109 being marginal remains inert. Relay 111 places ground potential on conductor 121 which may serve in the well known manner to associate the operator's head set with the connection, or 90 for any other suitable purpose.

When the operator is ready to record the designation on the sender she manipulates the dial 112 in accordance with the digits of the called number. When the dial is moved away 95 from normal on the first digit, the springs 113 close and complete a circuit from battery through the resistance 115, springs 113, contact and winding of relay 109 to ground at the contact of key DK. This shunts the relay 100 111 which releases and permits the relay 109 to operate and lock through its left armature and contact. Relay 109 at its right armatures includes the tip and ring conductors in series with the contacts 114 of the dial 112. The 105 dial on returning opens and closes the circuit leading to the impulse relay in the sender and the number is recorded in the well-known manner. After the dialing has been completed the operator releases the key DK releasing relay 109. Relay 109 disconnects the dial and includes the relay 108 across the tip and ring conductors of the cord.

During the registration the relay 214 is 115 energized in circuit from battery through its winding, upper and lower left contacts of spring 215, brush 216, conductor 217 and thence to ground in the sender. When the sender is prepared, the fundamental control circuit is completed from battery to the winding of relay 200, conductor 223, lower left contact of spring 207, lower contacts of spring 224, conductor 225, brush 225 and thence through the stepping relay in the sender to ground. Relay 200 in operating closes the circuit for driving the sequence switch out of 120 position 4 and into position 5. When the sequence switch 205 reaches position 4 1/4 the fundamental circuit is modified so as to lead from battery through the winding of relay 125 130

200, lower contact of spring 218, right contact of relay 200 and thence over the lower contacts of spring 224 as above traced.

The brush selection is now made in the

- 5 group selector by operating the brush tripping spindle 236. The circuit for the trip spindle magnet 227 may be traced from battery through the winding thereof, lower contacts of spring 213 to ground at the front contact of relay 200. As the trip spindle rotates the interrupter springs 237 open and close to place a shunt around the winding of the stepping relay in the sender. This shunt may be traced from ground through the springs 237, 10 lower right contact of spring 207 to the winding of relay 200. This shunt circuit holds the relay 200 and releases the stepping relay in the sender. When the sender has been satisfied, the fundamental circuit is opened and 15 relay 200 releases. Relay 200 on releasing opens the circuit of the magnet 227 stopping the tripping spindle in position to trip the proper set of brushes and closes a circuit at its back contact for driving sequence switch 205 out of position 5. As the sequence switch reaches position $5\frac{3}{4}$ relay 200 is again operated in a circuit from battery through its winding, conductor 223, upper left contact of spring 207, back contact of relay 208, upper 20 right contact of spring 209 to ground. Relay 200 opens the circuit of the sequence switch causing it to stop in position 6.

The brush carriage is now rotated by the power magnet 232 to select an idle trunk.

- 35 The circuit for magnet 232 leads from battery through its winding, left hand contacts of spring 213 to ground at the front contact of relay 200. During the movement of the brushes from one trunk to another a test circuit is completed from ground through the lower right contact of spring 209, right hand high resistance winding of test relay 208, upper left contact of spring 228, test brush 229 to the test terminals of the successive trunks. When an idle trunk is reached the proper potential is found thereon to operate the test relay 208. Relay 208 at its back contact releases the relay 200 which opens the circuit of magnet 232 and closes a 40 circuit for driving the sequence switch through position 7 and into position 8. The test relay 208 in operating substitutes its left hand low resistance winding for the right winding, thus rendering the selected trunk 45 non-selectable to other switches.

The apparatus is now in condition to operate the second group selector shown in Fig. 3 to further extend the connection. The fundamental circuit for controlling the group

- 50 selector shown in Fig. 3 may be traced from the sender over the brush 225, conductor 235 lower right and upper left contacts of spring 224, brush 233, thence over the ring side of the trunk to the succeeding selector and returning over the tip side of the trunk through

the brush 234, upper back contact of relay 246, lower contacts of spring 244, conductor 238, brush 226 to the sender. In the manner already explained in connection with the first group selector, the second group selector is 70 operated to make brush selection and to position its brushes 306, 307 and 308 on the terminals of an idle trunk leading to the final selector switch shown in Fig. 4.

Upon the seizure of the final selector a circuit is completed for operating the relay 406. This circuit may be traced from battery through both windings of said relay, left contacts of spring 417, sleeve conductor 433 to the grounded brush 308. Relay 406 locks 80 through both its windings and left front contact and the normal contact of relay 403 to conductor 433.

Next the final selector is positioned under the control of the register sender and for this purpose the fundamental circuit is completed from battery through the winding of relay 400, lower and upper left contacts of spring 416, conductor 430, thence over the ring side of the trunk through the terminal and brush 90 307, contact of spring 302, thence as previously traced to the sender 260 and returning over the tip side of the trunk through the upper contacts of spring 303, brush 306 to ground at the upper contact of spring 402. 95 Relay 400 operates and locks through its winding and left contact and the upper left contact of spring 401 to the ring conductor of the trunk. Relay 400 at its right front contact completes a circuit leading through the 100 lower right contact of spring 419 and the magnet 405 of the sequence switch for driving said sequence switch out of position 1 and into position 2. In position 2 the brush tripping spindle magnet 422 is energized in 105 a circuit from battery through its winding, lower left and upper right contacts of spring 418 to ground at the front contact of relay 400. Magnet 422 rotates the brush tripping spindle to select the proper set of brushes and 110 the interrupter springs 431 are opened and closed to place a short-circuiting path around the stepping relay in the sender. This path may be traced from ground through the springs 431, upper right and lower left contacts of spring 416 to the winding of relay 400. When the sender has been satisfied, the fundamental circuit is opened and relay 400 releases opening the circuit of the magnet 422, causing the tripping spindle to cease 115 120 rotating. Relay 400 at its back contact completes a circuit leading to the lower left contact of spring 419 for driving sequence switch 405 into position 3.

When the sender is again ready, the fundamental circuit is reclosed and relay 400 operates to close a circuit for driving the sequence 125 405 out of position 3 and into position 5. The relay 400 locks as before explained and with sequence switch 405 in position 5 130

the brush carriage power magnet 423 is energized. The circuit for magnet 423 leads from battery through its winding, right hand contacts of spring 418 to ground at the front contact of relay 400. Magnet 423 rotates the brush carriage. As the brushes 424, 425 and 426 pass each set of terminals, the interrupter springs 432 are opened and closed to short-circuit the stepping relay in the sender. 5 The path for short-circuiting this relay may be traced from ground through the springs 432, upper right and lower left contacts of spring 416 to the winding of relay 400. As soon as the brushes 424, 425 and 426 reach 10 the terminals of the called line 427, the fundamental circuit is opened in the sender causing the release of relay 400. Relay 400 opens the circuit of the power magnet 423 and closes the circuit for driving the sequence switch 15 20 405 out of position 5.

As the sequence switch passes from position 5 1/4 to position 6 the called line 427 is tested to determine its busy or idle condition. The test circuit leads from the brush 426, 25 winding of test relay 420, contact of spring 421, resistance 428, lower right contact of spring 413 to ground. If the line is idle relay 420 operates and locks through its left front contact to ground at the right front contact 30 of relay 406. The sequence switch 405 continues to rotate until it reaches position 10.

When the sender has completed its control of the final selector, it opens the circuit of relay 214 and this relay releases. Relay 200 now operates in a circuit through the upper 35 left contact of spring 218 and the back contact of relay 214. Relay 200 completes a circuit for driving the sequence switch 205 out of position 8 through position 9 and into position 10. As the sequence switch 205 moves 40 into position 10 the slow release relay 204 is energized in a circuit from battery to its right winding, lower contact of relay 240, lower left winding of repeating coil 242, 45 lower right and upper left contacts of spring 201, thence over the ring side of the connection to the operator's cord circuit, thence through the relay 108 as previously traced and returning over the tip side of the connection 50 through the lower left and upper right contacts of spring 202, upper left winding of coil 242, upper contact of relay 240, left winding of relay 204 to ground. Relay 204 operates the slow relay 247 in a circuit 55 from battery through the winding of the latter relay, upper contact of spring 248 to ground at the contact of relay 204. Relay 247 closes an obvious circuit over relay 214. With relay 214 again energized a circuit is 60 closed for holding the relay 200 traceable through the upper right contact of spring 218 to ground at the front contact of relay 214.

The circuits are now in condition to 65 determine the character of ringing current that

is necessary to operate the bell of the called subscriber on the party line 427. If the party line 427 has two substations 434 and 435 it will also have two sets of terminals. The upper set of terminals appearing in the final selector switch shown relate to the substation 434. The lower set of terminals relating to the substation 435 appear in another group of selector switches. Each selector is equipped with a ringing source 436, 437. By reversing 70 the tip and ring conductors of the party line one substation is signaled when the line is seized by one group of connectors whereas the other substation is signaled when the line is seized by the other group of connectors. 75 Inasmuch as ringing current is supplied from the first group selector switch shown in Fig. 2 when the toll operator recalls, it is necessary to provide some identifying means in the final switch. This means consists of a resistance element 438. In one group of final selectors the resistance element 438 is provided in series with the resistance 439. In the other group of final selectors the resistance 438 is omitted and the resistance 439 is connected 80 directly to the upper right contact of spring 412. In the present instance assume that the substation 434 is called and that the final selectors having access to this substation are equipped with the resistance 438. When the sequence switch 405 reaches position 9 1/4, a circuit is completed from battery through the resistances 439 and 438, right contacts of 85 spring 412, conductor 430, thence over the ring side of the connection to the brush 233, lower back contact of relay 246, right contacts of spring 245, right windings of relays 250 and 251 to ground. These two relays serve to identify the substation called and to prepare for the application of either the ringing 90 source 252 or 253 when the toll operator recalls the called subscriber. Since the resistance 438 is included in the circuit traced the marginal relay 250 does not operate. Relay 251, however, operates and locks through its 95 left winding and contact, lower right contact of spring 248 to ground at the contact of relay 204.

Relay 251 in operating closes a circuit from ground through its outer left front contact, 100 upper left contact of spring 206, magnet 205 to battery. The sequence switch thereupon moves out of position 10 and into position 11 where it awaits the toll operator. As the sequence switch 205 leaves position 10 it opens 105 the circuit of relay 200 which releases. When the operator depresses ringing key R' K' ringing current is transmitted to operate the relay 241. The circuit may be traced from ringing source 117, contact of key R' K' 110 thence over the ring side of the connection through the lower left winding of coil 242, relay 241, condenser 255, upper left winding 115 of coil 242 and returning over the tip side of the connection to ground at the upper contact 120

of key R' K'. Relay 241 in operating closes a circuit from battery through the lower winding of relay 240, contact of relay 241, back contact of relay 243 to ground. Relay 240 in operating opens the circuit of relay 204, which however, being slow maintains its armature for an interval. Before the relay 204 can release to remove the holding ground potential from conductor 256, a substitute 5 ground is applied to this conductor through the inner lower contact of relay 240, left contact of relay 247 and the upper contact of spring 248. With the sequence switch 205 in position 11 as explained and the operator 10 applying ringing current to operate the relay 241, a circuit is closed for the relay 200. This circuit may be traced from battery through the winding of said relay, lower left and upper right contacts of spring 249, contact 15 of relay 241 to ground at the back contact of relay 243. Relay 200 at its front contact closes a circuit for driving the sequence switch 205 out of position 11 and into position 12. As sequence switch 205 leaves position 20 25 11 relay 200 releases. When the operator ceases to manipulate the ringing key R' K' relay 240 releases and relay 204 is again operated as explained.

The final selector is now ready to advance 30 into the ringing position. When the sequence switch 205 of the group selector reaches position 12 a circuit is closed from battery through the winding of relay 400, lower left contact of spring 416, lower left contact of 35 spring 415, resistance 440, thence over the tip side of the connection through the brush 234, upper back contact of relay 246, lower right and upper left contact of spring 244, upper right winding of repeating coil 242, 40 upper winding of relay 243 to ground. Relay 400 operates but due to the resistance 440 relay 243 remains inert. Relay 400 closes an obvious circuit for driving the sequence switch 405 out of position 10, through position 45 11 and into position 12. As the sequence switch moves out of position 11 relay 400 releases.

In position 12 ringing current is applied 50 from the immediate ringing source 436 in a circuit leading over the right contact of spring 407, brush 425, thence over the subscriber's line and returning by way of brush 424, upper right and lower left contacts of spring 404 through the winding of the ringing relay 403 55 to battery. Relay 403 does not operate until the subscriber removes his receiver. As soon after the sequence switch reaches position 12 as the interrupter 441 closes its lower contact, a circuit is completed through the lower 60 right contact of spring 415 and the winding of relay 400. Relay 400 operates, closing the circuit for advancing the sequence switch out of position 12 and into position 13. The closure of the interrupter 441 is of such brief 65 duration that relay 400 releases before se-

quence switch 405 can move out of position 13. As soon after the sequence switch reaches position 13 as the interrupter 441 closes its upper contact a similar circuit is completed for operating relay 400 to advance the sequence 70 switch out of position 13 into position 14. In position 14 ringing current from the machine ringing source 437 is applied to the called subscriber's line.

When the called subscriber answers the relay 403 operates and opens the holding circuit of relay 406. Relay 406 releases and at its back contact completes a circuit for moving the sequence switch 405 out of position 14. When sequence switch 405 reaches position 80 14½ relay 406 operates in a circuit from battery through its right winding, right contacts of spring 417 to ground. Relay 406 opens the driving circuit of sequence switch 405 causing the same to stop in position 15. 85 Relay 406 locks in a circuit from battery through both its windings, left contacts of spring 417 to the sleeve conductor 433. The final selector switch is now in its talking position. 90

With the subscriber's receiver connected across the line at the called substation a circuit is closed for the supervisory relay 243, traceable from battery through the lower winding of said relay, lower right winding of 95 coil 242, upper contacts of spring 245, lower back contact of relay 246 thence over the ring side of the connection to the final selector through the upper right contact of spring 401, brush 425, over the subscriber's line, brush 424, upper contacts of spring 404, thence over the tip side of the connection through the upper back contact of relay 246, lower right and upper left contacts of spring 244, upper right winding of the coil 242, upper winding of relay 243 to ground. Relay 243 operates and closes a circuit from ground through its front contact, lower contacts of spring 249, winding of relay 200 to battery. Relay 200 operates, closing the circuit for driving the sequence 100 switch 205 out of position 12 and into position 13. As the sequence switch leaves position 12 it opens the circuit of relay 200. The group selector shown in Fig. 2 is now in its talking position. 105

In position 13 of sequence switch 205, a circuit is closed from battery, through the lower winding of relay 240, right contacts of spring 249 to ground at the front contact of relay 243. Relay 240 operates and opens the circuit 110 of relays 204 and 108. Relay 108 extinguishes the lamp 116 as a signal to the operator that the called subscriber has answered.

At the end of conversation the subscribers 115 replace their receivers. The called subscriber in replacing his receiver releases the relay 243 which releases the relay 240 including the relay 204 in series with relay 108. Relay 108 operates the lamp 116 as a signal to the toll operator. In the well known manner the re- 120 125 130

placement of the calling subscriber's receiver gives a signal to the toll operator. The operator takes down the connection by disconnecting her cord circuit. This causes the release of relay 204 which in turn releases relays 247 and 214. Relay 200 operates in a circuit over the left contact of spring 218 and the back contact of relay 214. Relay 200 completes a circuit for driving the sequence switch 205 out of position 13 and into position 17. In this position the brush carriage is restored to normal. The circuit for the magnet 232 leads over the left contacts of spring 213 and the front contact of relay 200. The relay 208 is in a deenergized condition at this time since its circuit was opened when the sequence switch moved out of position 13. Relay 200 is energized at this time in a circuit from battery, through its winding, upper left contact of spring 207, back contact of relay 208, upper right contact of spring 209 to ground. When the brush carriage reaches its normal position, a circuit is closed from battery, through the normal contact and brush 257, upper right contact of spring 228, right winding of relay 208, lower right contact of spring 209 to ground. Relay 208 operates and releases relay 200 which opens the circuit for the power magnet 232. It will be noted that the tripping spindle 236 is restored as soon as the sequence switch 205 reaches position 12. The circuit for this purpose may be traced from battery, through the winding of magnet 227, right contacts of spring 215, to ground through the springs 237.

The opening of the sleeve lead causes the release of the second group selector shown in Fig. 3 in the usual manner.

The opening of the sleeve lead also releases the relay 406 in the final selector. Relay 406 completes a circuit over the spring 419 for driving the sequence switch 405 out of position 15. If the called subscriber has replaced his receiver, relay 406 remains deenergized and sequence switch 405 is driven into position 17. In this position the tripping spindle is restored to normal by means of a circuit from battery, through the winding of magnet 422, lower left and upper right contacts of spring 418 to ground at the front contacts of relay 400. Relay 400 is energized at this time in a circuit from battery through its winding, lower contacts of spring 416 to ground through the springs 431. When the tripping spindle is restored spring 431 opens and releases relay 400 in turn opening the circuit of the magnet 422. Relay 400 in releasing closes a circuit for driving the sequence switch out of position 17 and into position 18. The brush carriage is restored by means of a circuit from battery, through the winding of magnet 423, lower right and upper left contacts of spring 418 to ground at the back contact of relay 400. When the

brush carriage is completely restored, relay 400 operates in a circuit from battery, through its winding, lower left contact of spring 416, upper left contact of spring 415 to ground through the brush 432. Relay 400 opens the circuit of the power magnet 423 and closes a circuit for driving the sequence switch into position 1.

It will next be assumed that the called subscriber's line is busy at the time it is tested. The relay 420 therefore fails to operate and when the sequence switch reaches position 8 3/4 the relay 400 energizes. The circuit may be traced from battery, through the winding of said relay, spring 414, back contact of relay 420, to ground at the contact of relay 406. Relay 400 opens the circuit of the sequence switch causing it to stop in position 9. In this position a busy signal is sent back to the toll operator. For this purpose the relay 408 is operated in a circuit from battery, through its right winding, right contacts of spring 409 to ground at the front contact of relay 400. Relay 408 completes a circuit from battery, through the interrupter 442, right contact of relay 408, right contact of spring 402, thence over the tip side of the connection, right contacts of spring 244, upper winding of relay 240 to ground, through the left back contact of relay 251. Relay 240, under the control of interrupter 442, operates and releases intermittently, opening the circuit of relay 108 in the operator's cord circuit. This causes the lamp 116 to flash indicating that the line is busy. The operator causes the release of the apparatus in the well known manner.

It will next be assumed that after the conversation has been completed the called subscriber is the first to hang up his receiver and that the toll operator wishes to recall him without releasing the connection. At this time it will be remembered, the sequence switch 205 is in position 13 and the sequence switch 405 is in position 15. To recall, the toll operator manipulates her ringing key R' K' to operate the relay 241 as previously explained. Relay 241 operates relay 240 and a circuit is now closed for relay 246. This circuit leads from battery, through the winding of relay 246, inner right contact of relay 251, lower right contact of spring 254, inner upper contact of relay 240, back contact of relay 243 to ground. Relay 246 connects the ringing source 252 with the tip and ring conductors of the connection leading to the called subscriber's line. The ringing circuit is traced from the source 252, right back contact of relay 250, outer right front contact of relay 251, lower front contact of relay 246, thence over the ring side of the connection, through the subscriber's line and returning over the tip side to ground at the upper front contact of relay 246. This ringing source is the proper kind to operate the subscriber's

bell at substation 434. Had the other substation 435 been called, then the relay 250 would have been operated and the source 253 connected to the line. In response to ringing current the subscriber again answers his telephone and further conversation may take place.

It has not been considered necessary to show all the details of the register sender 10 260 or to explain the manner in which it is operated and released since this is already well known and may be in general the same as disclosed in the patent to McBerty and Polinkowsky hereinbefore cited.

15 While the invention is shown in connection with switches of the rotary power driven type, it is to be understood that it is not limited to a system employing such switches, but may be applied as well to other types of 20 systems.

What is claimed is:

1. In a telephone system, telephone lines, a series of selective switches, means for operating said switches to extend a connection 25 to a called telephone line, a plurality of sources of ringing current, each associated with a different switch in said series, and means for applying ringing current to the called line from all of said sources.

30 2. In a telephone system, telephone lines, a series of selective switches, means for operating said switches to extend a connection to a called telephone line, a plurality of sources of ringing current, each associated 35 with a different switch in said series, automatically operated means for applying ringing current to the called line from one of said sources, and manually controlled means for applying ringing current to the same called line from another of said sources.

35 3. In a telephone system, telephone lines, a series of selective switches, means for operating said switches to extend a connection to a called telephone line, a plurality of sources of ringing current, each associated 45 with a different switch in said series, an operator's position, automatic means for connecting one of said sources to a called line to call the subscriber, and means controlled by 50 the operator to connect another of said sources to the line to recall the subscriber.

4. In a telephone system, subscribers' lines, a group selector and a final selector switch, means for operating said selectors in succession 55 to extend a connection to a called line, a separate source of ringing current associated with each selector, and means for applying current to the same called line from both of said sources.

60 5. In a telephone system, telephone lines, a series of selective switches, means for operating said switches to extend a connection to a called telephone line, a source of ringing current associated with one of said selective switches, sources of ringing current of dif-

ferent character associated with a second switch in said series, and means for applying to a called line ringing current from any of said sources.

6. In a telephone system, party lines, a series of selective switches, means for operating said switches to extend a connection to a called line, a source of ringing current associated with the final one of said switches for signaling the subscribers on a party line, 70 sources of ringing current associated with a preceding selector in the series, means effective when a party line is called for connecting thereto the source associated with the final selector, and means effective while the same 80 talking connection is maintained to the called line for connecting one of the sources associated with the preceding selector to said called line.

7. In combination, subscribers' lines, a series of selectors for extending a connection to a called line, a plurality of ringing sources associated with one of said selectors, a variably applicable source associated with a subsequent selector in the series, means for connecting to a called line the source at said 90 subsequent selector, and selective means controlled by said subsequent selector for connecting to the called line the desired one of said sources at said first selector. 95

8. In combination, subscribers' lines, a series of selectors for extending a connection to a called line, a plurality of ringing sources associated with one of said selectors, a variably applicable source associated with a subsequent selector in the series, means for connecting to a called line the source at said 100 subsequent selector, identifying means in said first selector, means for setting said identifying means according to the manner current is applied at the subsequent selector, and means controlled by said identifying means for selectively connecting to the called line one of the sources at said first selector. 105

9. In combination, party lines, a series of selector switches for extending a connection to a called party line, ringing sources of different character associated with one of said switches, a ringing source associated with a subsequent switch in the series, means dependent on the party called for variably connecting to the line the source of current at said subsequent switch, means dependent on the party called and controlled from said subsequent switch for establishing in said first 110 switch a record identifying such party, and means controlled by said identifying record for selectively connecting to the called line one of the sources at said first selector. 115

10. In combination, party lines, a plurality 125 of groups of final selector switches, each group having access to said lines for the purpose of calling a different party thereon, a group selector switch for extending a connection to any one of said final selector 130

switches, a source of ringing current associated with each of said final selector switches, sources of ringing current associated with said group selector, means dependent on the party called for variably connecting to the called line the source of ringing current at the final selector, and identifying means in said group selector operable in accordance with the group of final switches to which the connection is extended for selectively connecting to the called line one of the sources of ringing current at said group selector.

11. In a telephone system, subscribers'

lines, a series of selector switches for extending both local and toll connections to a called line, a source of ringing current in the final selector for signaling the called line on both local and toll calls, a source of ringing current associated with a preceding selector in said series, and means for rendering said last source effective to signal the called line when a toll call is extended thereto.

In witness whereof, I hereunto subscribe my name this 28th day of April, A. D. 1927.

GEORGE THOMPSON.
